DESIGN FOR A TWIN VISION TRANSPARENCY VIEWER

Richard P. Fuller, Los Angeles, Calif.

Application August 20, 1947, Serial No. 140,955

Term of patent 14 years

(Cl. D61—1)

To all whom it may concern:

Be it known that I, Richard P. Fuller, a citizen of the United States and a resident of Los Angeles, California, have invented a new, original, and ornamental Design for a Twin Vision Transparency Viewer, of which the following is a specification, reference being had to the accompanying drawing, forming part thereof.

Referring to the drawing:

Figure 1 is a top plan view of a twin vision transparency viewer, showing my new design;

Figure 2 is a side elevation of the viewer as seen from the under side of Figure 1;

Figure 3 is a rear elevation of the viewer;

Figure 4 is a bottom plan view thereof, and

Figure 5 is a front elevation thereof.

I claim:

The ornamental design for a twin vision transparency viewer, as shown.

RICHARD P. FULLER.
